 Rachel Gilboy(57) **CLAIM**

The ornamental design for a pneumatic tube jumping toy, as shown and described.

DESCRIPTION

FIG. 1 is a front elevation of a pneumatic tube jumping toy; FIG. 2 is a rear elevation of the pneumatic tube jumping toy; FIG. 3 is a right side elevation of the pneumatic tube jumping toy;

FIG. 4 is a left side elevation of the pneumatic tube jumping toy;

FIG. 5 is a top plan view of the pneumatic tube jumping toy; and,

FIG. 6 is a bottom plan view of the pneumatic tube jumping toy.

The broken lines in the drawings illustrate portions of the pneumatic tube jumping toy that form no part of the claimed design.
